*T. & A. Parkes.
Printing Press.*

No 15437.

Patented Jul 29. 1856.

Fig. 1.

Fig. 2.

UNITED STATES PATENT OFFICE.

THOMAS PARKES AND ALFRED PARKES, OF BROOKLYN, NEW YORK.

PRINTING-PRESS.

Specification of Letters Patent No. 15,437, dated July 29, 1856.

To all whom it may concern:

Be it known that we, THOMAS PARKES and ALFRED PARKES, of Brooklyn, in the county of Kings and State of New York, have 5 invented a new and Improved Printing-Press; and we do hereby declare that the following is a full, clear, and exact description of the same, reference being had to the annexed drawings, making a part of this 10 specification, in which—

Figure 1, is a longitudinal vertical section of our improvement, the plane of section being through the center. Fig. 2, is a plan or top view of the same.

15 Similar letters of reference indicate corresponding parts in the two figures.

Our invention consists, 1st, in the employment or use of rotating printing cylinders fitted in vibrating bearings and connected by gearing with a cylinder having flat forms attached to its periphery, as will be presently shown and described, whereby impressions may be taken from flat forms on a rotating cylinder in an expeditious and 25 perfect manner.

2nd, our invention consists in the peculiar means employed for feeding or presenting the sheets to the printing cylinders whereby both sides of the sheets may be printed 30 upon before they leave the machine.

3rd, our invention consists in the peculiar device or means employed for feeding two or more printing cylinders from one feed board and presenting the sheets to one fly.

35 To enable others skilled in the art to fully understand and construct our invention, we will proceed to describe it.

A, represents a framing, which may be constructed in any proper manner to support the working parts.

B, represents a cylinder having two segments, or portions cut off, so as to leave or form, at opposite points on its periphery, two flat surfaces α , α , on which the forms 45 are placed or secured.

C, C, are two ink rollers, the axes of which are fitted in bearings b , b , which are attached to rods c , said rods working in guides and having spiral springs around 50 them, which springs keep the rollers C, pressed upon the periphery of the cylinder B, and forms on the flat surfaces α , α .

D, D, represent two printing cylinders, which are provided with fingers d , attached 55 to rods e , fitted within the cylinders, said cylinders being hollow and the fingers pro-

jecting through longitudinal slots f , made in their peripheries. Each rod has two levers g pivoted to an arm h , the arms being attached transversely to the rods and the 60 ends of the levers passing through slots or openings in the peripheries of the cylinders, see Fig. 1. One end of each cylinder D, has a toothed flanch E upon it, and each flanch gears into a toothed flanch F, at one end of 65 the cylinder B. The axes of the printing cylinders D, D, are fitted in sliding or vibrating bearings i , which work in boxes j , attached to each side of the framing A. Each bearing has a rod k , attached to it, 70 said rods having friction rollers on their outer ends, the rollers being fitted in grooves l , made in the sides of the cylinder B, the grooves corresponding in form to the periphery of the cylinder, with the exception 75 that they are slightly concave under the parts α , α , see dotted lines, Fig. 1. By means of the grooves l , and sliding bearings i , the cylinders D, D, are moved in and out to conform to the shape of the cylinder B, 80 that is, they are made to bear upon the whole surface of the flat portions α , α , but not upon the cylindrical portions (which are reserved for ink distribution), in consequence of the bearings sliding in their 85 boxes j .

G, represents the feed board which rests upon spiral springs m , placed on vertical rods n attached to a cross bar in the framing. The rods n , pass, one through each 90 corner of the feed board and serve as guides to the feed board.

H, represents the fly board which is below the feed board and arranged in a similar manner, being placed on springs o , which 95 are around rods p , said rods passing through the corners of the fly board.

In the framing A, there are placed transversely, three shafts q , q' , q'' , each of which has a series of pulleys r , upon it, and s , is 100 a shaft, the ends of which are fitted in elastic or yielding bearings t , the upper ends of which are connected by a cross rod u , against which a cam or wiper wheel v , on a shaft w , acts. The shaft w , is rotated by means of connecting rod x , attached to cranks y , which are actuated by cams I, I, on the ends of the shaft of the cylinder B. The shaft s , is placed directly over the shaft q , and has pulleys z , upon it, around which, tapes 1, 105 pass, said tapes passing around pulleys 2, on a shaft 3, which is placed between ver-

tical sliding bars 4, 4, in the framing A. Two other shafts 5 and 6, are also placed between the same sliding bars, the shafts 3, 5, 6, being placed one over the other, as 5 clearly shown in Fig. 1. The shafts 5, 6, have each pulleys 7, 8, upon them around which, tapes 9, 10, pass. The tape 9 passes over the pulleys r , on the shaft q , and under pulleys on a shaft 10, and around 10 pulleys on a shaft 12, thence backward underneath pulleys on a shaft 13, and over the pulley r , on the shaft q' , and around the pulleys 7 on the shaft 5, the tapes 9 forming endless belts, see Fig. 1. The tapes 10, 15 pass around pulleys on a similar shaft 14, 15, and around the pulleys 8 and r , on the shafts 6, q' and q'' , the latter tapes also forming endless bands as shown clearly in Fig. 1. The sliding bars 4, 4, are operated 20 by eccentrics J, J, which are placed on a shaft K in the framing A.

a' , a'' , a''' , are three shafts which are placed one over the other in the framing A. These shafts are each provided with a series 25 of pulleys around which, tapes b' , b'' , b''' , pass, the tapes b' , on the upper shaft a' , pass around pulleys on a shaft o' , the tapes b'' , pass around pulleys on a shaft d' and the tapes b''' , pass around pulleys on a 30 shaft e' .

Around the upper printing cylinder D, two tapes f' , f'' pass; these tapes pass around pulleys on a shaft g' , the ends of which work in rods h' , which are attached 35 to the sliding bearings i' ; the shaft g' , consequently works back and forth with the cylinder D. The shaft d' , around the pulleys of which, the tapes b'' pass, has its bearings in arms h'' , which are attached to a shaft i' , 40 one of said arms having a rod j' , attached to it. The lower end of the rod j' , has a horizontal arm k' attached to it.

K' , is a shaft which has two cams or eccentrics upon it, one of which L, is shown 45 in Fig. 1. The cam L, bears against a sliding frame M, which has an inclined plane on one of its sides, said inclined plane, a'''' , acting upon the rod j' . Within the frame M, there is placed a pulley k'' , around 50 which, a tape or belt l' passes, said belt also passing around a pulley on the shaft e' . A belt m' , passes around the lower printing cylinder D, said belt also passing around a pulley on a shaft n' , which passes through 55 a slot in the sliding frame M. A shaft o' , also passes through a slot in the sliding frame M, said shaft having a pulley p' , upon it, around which pulley, a belt g'' , passes, said belt also passing around a 60 pulley on the shaft 14. The two shafts n' , o' , have pulleys upon them, around which a cross belt s'' , passes. Below the three shafts a' , a'' , a''' , there are placed three shafts t' , u' , v' , which have tapes passing 65 around them, and these tapes pass over

pulleys on shafts arranged relatively with the lower cylinder D, precisely as those previously described.

The operation is as follows. The sheets, to be printed, are placed upon the feed board G, in a pile, or one on the top of the other, as shown in blue, Fig. 1, and motion being given the shaft of the cylinder B, said cylinder is rotated and also the printing cylinders D, D, and ink rollers C, C, 70 the ink rollers inking the forms on the flat surfaces a , a' , of the cylinder B. The shaft s is moved down or depressed, by the cam v, and the top sheet of paper, having been placed by hand, passes between its pulleys z , and the pulleys r , on the shaft q , said sheet passing up between the tapes 1 and 9, and then between the tapes b' , b'' . The sliding bars 4, 4, being moved upward at this period by the cams J, so that the tapes 1, 80 9, may conduct the sheet between the tapes b' , b'' , as shown in Fig. 1, the sheet being indicated by blue arrows. The end of the sheet passes upon the shaft g' and is grasped by the fingers d, and carried around the upper cylinder D, and receives its impression from one of the forms, the sheet, printed on one side, then passes upon the tapes b''' and the shaft d' , drops or falls a trifle, the lower end of the rod j'' , having 85 the inclined plane, a'''' , moved from underneath it, and the sheet passes between the tapes b' , b'' , and stops a short time, till the other form on the cylinder B, reaches a proper point. When the sheet moves backward and is again caught by the fingers on the upper cylinder D, and the opposite side of the sheet receives its impression from the other form. The dwell or cessation of the movement of the sheet, is produced at the 90 proper time by the cam I, which actuates the slide M, and the reverse movement of the tapes is produced by causing the pulley k'' , to bear alternately against the pulleys on the shafts n' , o' , the movement of the 100 sliding frame M, producing this effect, and the dwell of the tapes being produced in consequence of the pulley k'' , being a short time free from contact with either of the pulleys n' , o' , but held by the friction 110 shoe k'''' .

The sheet, when printed on both sides, is conveyed back between the tapes b'' , b''' , and down between the tapes 9, and 10, and passes underneath the heel of a fly A', which 120 is operated by pins 1 x , on one of the cams J, said fly depositing the sheet upon the fly board H.

When the bars 4, 4, descend, the succeeding sheet is carried by the lower tapes to the lower cylinder D, in the same manner, precisely, as the one just described, consequently 125 two printing cylinders are fed from one feed board and each sheet has both sides printed, the sheets receiving the impression, first 130

from one form and then from the other. As the feed and fly boards rest upon springs, they will gradually rise and fall as the paper accumulates and diminishes upon them.

5 The fingers d , are operated at the proper time, in consequence of the levers g, g , coming in contact with projections x^x, x^x , on the cylinder B.

10 The belts 9 and 10, are kept taut by vibrating tighteners y^x, y^x .

Having thus described our invention, what we claim as new and desire to secure by Letters Patent, is—

15 1. The cylinder B, having flat surfaces a, a , on its periphery, to receive the forms, in combination with the printing cylinders D, D, placed in sliding bearings, and arranged substantially as shown and described,

20 for the purpose set forth.

2. We claim the reciprocating shafts 3, 5, 6, and stationary shafts $a', a'', a''', t' u', v'$, with the tapes arranged as shown, whereby the two printing cylinders D, D, are fed from one feed board and the sheets therefrom, when printed on both sides, deposited upon one and the same fly board.

25 3. We claim the sliding frame M, arranged and operating substantially as shown, whereby the motion of the belt, l' , 30 is reversed at the proper time, and also stopped at proper intervals and the shaft d' , raised and lowered, for the purpose of reversing the movement of the sheets and causing them to be printed on both sides. 35
